1,024,104 AUTOMATIC PLAYING
ATTACHMENT FOR MUSICAL IN-
STRUMENTS. Robert J. BENNETT,
Moline, Ill. Filed May 9, 1910. Serial
No. 560,263.

To all whom it may concern:

Be it known that I, Robert J. BENNETT, a citizen of the United States, residing at Moline, in the county of Rock Island and State of Illinois, have invented certain new and useful Improvements in Automatic Playing Attachments for Musical Instruments, of which the following is a full, clear, and exact specification.

This invention relates to pneumatic, automatic playing attachments for musical instruments, and more particularly to those employing a record sheet serving to control air passages usually called "tracker ducts", which are connected with pneumatics for controlling the instrumentalities whereby the notes are sounded.

Some musical instruments of this nature are designed to play a solo instrument and an accompaniment instrument by one and the same record sheet. Sometimes, with such an apparatus, it is desirable to play only one of the instruments, the accompaniment instrument, for example, by the same sheet, and at such times the devices peculiar to the solo instrument must be rendered functionless.

This invention relates more particularly to means for using two tracker boards, or two separate series of tracker ducts for the solo and accompaniment instruments respectively, in conjunction with one and the same record sheet, and rendering one tracker board inoperative without disturbing the other when it is desired to cut out one of the instruments, and the invention has for its primary object to provide an improved automatic playing attachment having means for the accomplishment of these ends.

Another object of the invention is to so arrange the tracker boards with relation to one another as to make them engage opposite sides of the sheet, and thereby mutually contribute to the degree of pressure required for perfect contact of the sheets against their respective faces.

Another object of the invention is to automatically close communication between one set of the note sounding instrumentalities and its tracker ducts when it is desired to cut out that instrument.

With a view to the attainment of these ends, the invention consists in the features of novelty which will now be described with reference to the accompanying drawings, and more particularly pointed out in the claims.

In the said drawings—Figure 1 is a diagrammatic illustration of an automatic playing attachment for musical instruments embodying this invention. Fig. 2 is a detail view of a lock and valve hereinafter de-

scribed. Fig. 3 is a front elevation, partly broken away, of the tracker board and record sheet. Fig. 4 is a detail sectional view of one of the tracker boards and the cut-out valve and connected parts.

1 is the record sheet capable of being unwound from one spool 2 on to another spool 3, and 4 is the ordinary or usual tracker board over which the sheet 1 passes, and which is provided with tracker ducts 5 terminating in openings 6 in the face of the tracker board and having connection of some suitable sort, as by tubes 7, with one of the musical instruments to be actuated for sounding the notes thereof when the openings 8 of the record sheet register therewith. The musical instrument with which the tracker ducts 5 are connected is not illustrated in detail, but is indicated diagrammatically at 9, and comprises an organ, piano, or other musical instrument, together with means whereby the admission of air to the tracker ducts 5 through the openings 8 of the sheet 1 results in the actuation of the note sounding instrumentalities of the instrument 9. There are many examples of pneumatic devices well known in the art capable of thus setting into operation the note sounding instrumentalities of a musical instrument when air is admitted thereto through a duct or other passage, such as the passage 5, and the diagrammatic illustration 9 may be regarded as comprising any one of these suitable for the purpose. For the purposes of this explanation, the instrument 9 may be regarded as the accompaniment instrument, and 10 may be regarded as the solo instrument, which, like the instrument 9, should comprise pneumatic devices whereby the note sounding instrumentalities of this instrument 10 will be sounded or actuated when air is admitted to such devices to a suitable passage under proper control, such, for example, as the passage or pipe 11, in which a vacuum or partial vacuum is created, by suitable air exhausting devices or pumbers comprised within the solo instrument, as usual, similar exhausters or pumbers being comprised within the accompaniment instrument 9 for creating a vacuum or partial vacuum in the wind chest of that instrument, and a corresponding degree of vacuum in the tracker duct 5 in the usual or any suitable manner.

12 is a second tracker board which controls the solo instrument, and which is provided with one or more tracker ducts 13 terminating in tracker duct openings 14 arranged in line with note openings 15 in the record sheet 1, but out of line with the note openings 8, the tracker duct openings 6, 14 being arranged in two parallel horizontal rows, but in staggered relation to one another, so that lines drawn through the openings of one series perpendicular to that series will pass between the openings of the other series, and consequently, the set of note openings 8 intended for the

tracker ducts 5 will be ineffectual to admit air to the tracker ducts 13, and vice versa.

The tracker board 12 has its operative face 12^a presented inwardly or turned toward the face of the tracker board 4, so that the faces of these two tracker boards will engage opposite sides of the record sheet 1, but preferably not directly opposite one another, so that the contact of the sheet will be perfect with the face of each. In order that the tracker board 12 may be thus arranged at the outer side or face of the

sheet 1, without interfering with the spool 3, and that this board may be readily turned out of the way when it is desired to play the accompaniment instrument alone, such board 12 is pivotally mounted and preferably curvilinear in cross section, as shown in Fig. 1, so as to be turned back out of the way, and pass through an aperture 16 in a part of the case of the instrument. In order that the tracker board 12 may be thus manipulated, it is supported on centers 17 by arms 18, and when in operative position, is locked in place by any suitable means, such, for example, as a catch 19 arranged to engage with the upper end of a curved rub plate 20 secured to the inner face of a side member 21 of the frame. When the tracker board 12 is being turned back out of the way, the catch 19 rides on the face of the rub plate 20 until it reaches the lower end of the latter, when it drops off and engages therengainst for holding the tracker board in its inactive position, and when being turned up in place, the catch 19 slides over the rub plate 20 until it drops off at the upper end thereof and engages therewith, as shown in full lines in Figs. 1 and 2. For convenience of manipulation, catch 19 is mounted upon a slide 22 having slots 23 through which screws 24 pass into the tracker board 12, the slide 22 having a handle 25 arranged adjacent a fixed thumb piece 26 for facilitating withdrawal of the catch 19 against the action of a spring 27 situated between the end of the tracker board 12 and the catch 19 for holding the latter in engagement.

It is quite apparent that when the tracker board 12 is withdrawn from the record sheet 1, the solo instrument 10 would be objectionably sounded if the passages 11 communicating with the tracker duct openings 13 respectively were not first closed against the admission of air. In order that this may be accomplished, suitable means are provided whereby the withdrawal of the catch 19 preparatory to unlocking the tracker board 12 will automatically cut out the solo instrument by closing the passages 11. To that end, the tracker ducts 13 are each connected with a chamber 28 by separate pipes or passages 29, and the pipes or tubes 11 are connected with chambers 30 respec-

tively, which are respectively arranged adjacent the chambers 28, and both open into a chamber 31 divided into two compartments by a flexible diaphragm 32, or other suitable movable abutment capable of being influenced by variation in the pressure maintained in chamber 31 with respect to the pressure existing in chambers 28, 30, the latter being capable of communicating with one another via the chamber 30 at one side of the diaphragm 32. The chamber

31 is susceptible of variations in air pressure or degree of vacuum by the manipulation of a valve 33 carried by or operated in unison with the catch 19 in such a way that when the valve 33 is withdrawn with the catch, resulting in a reduction of the degree of vacuum in chamber 31 above the diaphragm, the vacuum existing in chambers 28, 30 below the diaphragm 32 will induce the air pressure above to force the diaphragm to its seat over the chambers 28, 30, and thereby close communication between passages 11 and tracker ducts 13, and prevent the admission of air to the passage 11. When the tracker board 12 is in position for playing the solo instrument, the valve 33 closes a port 34 which would otherwise communicate with the atmosphere. This port is connected by tube 35 with a diaphragm chamber 36 closed on one side by diaphragm 37, and at the opposite side of this diaphragm is situated a chamber 38 connected with any suitable means for creating a vacuum or partial vacuum therein, such, for example, as a pumper or exhauster 39. The chambers 36 and 38 are also connected together around the diaphragm 37 by a small bleed hole 40, so that the same degree of vacuum created in chamber 38 will exist in chamber 36, while the valve 33 is closed, but should the valve 33 be opened, the sudden supply of air to chamber 36 could not be withdrawn as rapidly through the bleed hole 40 as the chamber 38 is exhausted, and consequently, at that time, the diaphragm will move upwardly or toward the chamber 38, and as it does so, it will shut off communication with a third chamber 41 by a valve 42 arranged to be influenced by diaphragm 37. This valve 42 under normal conditions, is open, and a second valve 43 carried on the same stem 44 as valve 42 closes chamber 41 against the admission of external atmosphere, and thereby keeps chamber 31 in communication with the chamber 38 through a passage 45 leading into the chamber 41 between the two valves, thus maintaining substantially the same degree of vacuum above the diaphragm 32 as that which exists below it in the chambers 28, 30, and as a consequence, the diaphragm 32 will be inert, allowing the passages 11 to remain in communication with the tracker duct openings 13, but as soon as the valve

33 is opened and this equilibrium at opposite sides of the diaphragm 32 is disturbed by the admission of atmospheric air to the chamber 31 via valve 43 and passage 45, the higher degree of vacuum in chambers 28, 30 will enable the air pressure above diaphragm 32 to force the latter downwardly and close these two chambers 28, 30.

What I claim is:

1. In an apparatus for the purpose described, the combination of a traveling record sheet having two records thereon running side by side in the same direction, two series of tracker devices arranged to engage on opposite sides of the sheet and operate simultaneously, and separate note-sounding instrumentalities operatively connected with the said two series of tracker devices respectively.

2. In an apparatus of the class described, the combination of a traveling record sheet, spools upon which said sheet is wound, a tracker board engaging one side of said sheet, a second tracker board engaging the opposite side of said sheet and curved partially around one of said spools, means whereby the last said tracker board is capable of swinging partially around said spool to disengage it from said record sheet, and note sounding instrumentalities controlled by said tracker boards respectively.

3. In an apparatus of the class described, the combination of a record sheet, having two series of note openings running side by side in the same direction, a series of tracker ducts arranged to register with one series of said note openings, a second series of tracker ducts arranged to register with the other series of said note openings, said two series of tracker ducts engaging opposite sides of said sheet simultaneously, means whereby the one of said series of tracker ducts may be moved away from the record sheet, separate note sounding instrumentalities operatively connected with said tracker ducts respectively, and means for closing communication between the movable series of said tracker ducts and one of said note sounding instrumentalities at will.

4. In an apparatus of the class described, the combination of a traveling record sheet, a tracker board having tracker ducts engaged by said sheet, said sheet having a series of note openings adapted to register with said tracker ducts, note sounding instrumentalities connected with and controlled by said tracker ducts and record sheet, a second tracker board movable with relation to said record sheet and adapted to engage the same, said second tracker board also having tracker ducts and the record sheet having a second series of note openings adapted to register therewith, note sounding instrumentalities controlled by said second tracker board and record sheet, a lock for holding said tracker board against

movement, and means operatively connected with said lock for disconnecting the operative connection between the second said tracker board and second said note sounding instrumentalities when said lock is released.

5. In an apparatus of the class described, the combination of a traveling record sheet, a series of tracker ducts arranged in operative relation thereto, said record sheet having note openings adapted to register with said tracker ducts, note sounding instrumentalities operatively connected with and controlled by said tracker ducts and record sheet, a second series of tracker ducts arranged in operative relation to said record sheet, the record sheet having a second series of note openings adapted to register with the second series of tracker ducts, note sounding instrumentalities operatively connected with and controlled by said series of tracker ducts and record sheet, pneumatically operative means for disconnecting the second series of tracker ducts with said note sounding instrumentalities including means for creating a degree of vacuum therein, said pneumatic means being adapted to operate when said vacuum is broken or reduced, and a manually controlled valve for breaking or reducing said vacuum at will.

6. In an apparatus of the class described, the combination of a traveling record sheet having a series of note openings, a series of tracker ducts adapted to register therewith, note sounding instrumentalities connected with and controlled by said tracker ducts, a second series of tracker ducts arranged in operative relation to said record sheet, a second set of note sounding instrumentalities embodying means for creating therein a degree of vacuum and adapted to become operative upon the breaking or reduction of the said vacuum, chambers or passages connected respectively with said second series of tracker ducts and the second said note sounding instrumentalities for admitting air thereto, and breaking or reducing said vacuum therein, a third chamber with which the first said chambers communicate, a movable valve in said third chamber adapted to close the said passages opening thereto when the degree of vacuum existing in the latter becomes greater than that existing in said third chamber, air exhausting means, a pneumatic valve mechanism adapted to connect said third chamber with the atmosphere and said air exhausting means alternately, said pneumatic valve mechanism embodying a movable abutment subjected on both sides to the tension created by said air exhausting means, and a manually controlled valve for reducing the air tension on one side of said movable abutment at will.

7. In an apparatus of the class described, the combination of a traveling record sheet

having two records thereon running side by side in the same direction, two tracker devices arranged to engage on opposite sides of the sheet and operate simultaneously, and

separate note sounding instrumentalities operatively connected with said tracker devices respectively.

8. In an apparatus of the class described, the combination of a traveling record sheet having two records thereon running side by side in the same direction, a separate set of tracker devices for each of said records, said sets of tracker devices being arranged to engage on the opposite sides of the sheet and operate simultaneously, a solo instrument operatively connected with one set of said tracker devices, and an accompaniment instrument operatively connected with the other said set of tracker devices.

9. In an apparatus of the class described, the combination of a flexible traveling record sheet having two sets of record openings therein, the openings of one set being staggered with relation to those of the other, two tracker boards engaging opposite sides of said sheet and having tracker ducts arranged in line with the openings of said records respectively, one of said tracker boards being movable with relation to the other whereby it may be utilized as a means of producing tension of the record sheet against both tracker boards, and separate note-sounding instrumentalities respectively connected with said tracker boards.

In testimony whereof I have signed my name to this specification, in the presence of two subscribing witnesses, on this 6th day of May A. D. 1910.

ROBERT J. BENNETT.
